US00D741142S

(12) **United States Design Patent**
Todd, Jr. et al.

(10) **Patent No.:** **US D741,142 S**
(45) **Date of Patent:** **** Oct. 20, 2015**

(54) **HINGE**

(71) Applicant: **Southco, Inc.**, Concordville, PA (US)

(72) Inventors: **John Joseph Todd, Jr.**, Springfield, PA (US); **James Joseph Ford**, West Chester, PA (US); **Todd Michael Schwanger**, Exton, PA (US)

(73) Assignee: **Southco, Inc.**, Concordville, PA (US)

(**) Term: **14 Years**

(21) Appl. No.: **29/453,529**

(22) Filed: **Apr. 30, 2013**

(51) LOC (10) Cl. **08-06**

(52) U.S. Cl.

USPC **D8/327**

(58) **Field of Classification Search**

USPC D8/323, 328, 327; D23/303; 4/236, 4/240; 16/225, 250, 682, 309, 235, 275, 16/244, 379, 390, 430, 241, 238, 245, 236, 16/243, 242, 385

(57) **CLAIM**

The ornamental design for a hinge, as shown and described.

DESCRIPTION

FIG. 1 is a front isometric view taken from above the right front corner of a hinge;

FIG. 2 is a rear isometric view taken from above the left rear corner of the hinge of FIG. 1;

FIG. 3 is a rear isometric view taken from below the left rear corner of the hinge of FIG. 1;

FIG. 4 is a top plan view of the hinge of FIG. 1;

FIG. 5 is a bottom plan view of the hinge of FIG. 1;

FIG. 6 is a front elevation view of the hinge of FIG. 1;

FIG. 7 is a rear elevation view of the hinge of FIG. 1; and,

FIG. 8 is an elevation view as viewed from the right side of the hinge of FIG. 1, the left side being a mirror image of the right side.

1 Claim, 4 Drawing Sheets
